[57] CLAIM

The ornamental design for an oscillating table top fan, as shown and described.

DESCRIPTION

FIG. 1 is a front elevational view of an oscillating table top fan showing my new design;
FIG. 2 is a right side elevational view thereof;
FIG. 3 is a left side elevational view thereof;
FIG. 4 is a rear elevational view thereof; and,
FIG. 5 is a top plan view thereof.
The bottom of the design is substantially flat and unornamented.
